UNITED STATES PATENT OFFICE.

JOHN THOMAS TEBBUTT, OF THREE RIVERS, QUEBEC, CANADA.

SHOE.

1,262,285.

Specification of Letters Patent.

Patented Apr. 9, 1918.

Application filed June 30, 1917. Serial No. 178,036.

To all whom it may concern:

Be it known that I, JOHN THOMAS TEBBUTT, a subject of the King of Great Britain, and resident of the city of Three Rivers, in the Province of Quebec, in the Dominion of Canada, have invented certain new and useful Improvements in Shoes, of which the following is the specification.

The invention relates to improvements in shoes as described in the present specification and illustrated in the accompanying drawings that form part of the same.

The invention consists essentially of the novel means employed for reinforcing the shoe and for assembling the parts to produce neater footwear.

The objects of the invention are to devise a shoe that will resist the tendency to spread and consequently rip and tear, to facilitate the manufacture of shoes and generally to provide a serviceable, comfortable and elegant shoe.

In the drawings, Figure 1 is a plan view of a leather insole, showing the upper lining and welt attached to an inturned flange of the insole, formed by a horizontally split layer and reinforcing tie straps extending laterally between the longitudinal parts of the flange and included in the same stitching with the welt upper and lining.

Fig. 2 is a cross sectional view on the line 3—3 in Fig. 1 and adding the filling and outsole.

Fig. 3 is a cross sectional view on the line 4—4 in Fig. 1 and adding the filling and outsole.

Fig. 4 is a plan view of a felt insole omitting the reinforcing tie straps and showing the leather facing bound around the felt and arranged for reinforcing the stitching.

Fig. 5 is a cross sectional view on the line 5—5 in Fig. 4.

Fig. 6 is a cross sectional view showing the felt sole with the reinforcing straps and upper, lining and welt.

Like numerals of reference indicate corresponding parts in each figure.

Referring to the drawings, the insole 1 whether in leather or felt is split horizontally as far back as the beginning of the heel portion and completely around the toe and rolled or molded into a stiff flange 2, said flange being preferably formed by a cutting 3 inwardly from the outer edge and a cutting 4 outwardly beyond the end of the cutting 3 and extending part way toward meet-

ing the latter, the leather or other material released by each cutting being turned from the insole surface and bunched to form said flange 2.

The numeral 5 indicates the welt, 6 the lining, 7 the upper, 8 and 8^a the sewing, 9 the knife cut for the sewing in the welt and 10 the bandage or reinforcing tie straps which at each of their ends take the lining 6 into the folds 11.

The lining 6, the upper 7 and the bandages or tie straps 10 are first sewn to the insole 1, through the two parts 3 and 4 of the flange 2 and then the welt 5 is sewn to said insole 70 and flange through said lining, upper and straps, the sewing 8 and 8^a passing through the folded ends of said straps and consequently the folds of the lining in said straps.

The straps cross the insole 1 at different 75 places throughout the length of the shoe, thus practically making the upper, lining and insole a seat for the foot understrapped by said tie straps or bandages which is particularly effective across the shank where 80 considerable pressure usually occurs on account of the narrowing of the shoe at that part and as the flange 2 is cut in the insole from both directions there is no tendency to tear away by a tug or pull in either direction 85 and further it may be mentioned that the formation of said flange leaves a comfortable flat upper surface across the insole.

The asbestos sole 12 extends between the heel and toe and inside the flange 2 and the 90 outsole is secured over that.

An antiseptic is used for all the parts in proximity to the foot of the wearer, thereby eliminating many disagreeable features incident to footwear.

The asbestos sole is attached preferably by a wheat flour paste, as being the least liable of the adhesives to deteriorate and foul the shoe.

The insole in felt is covered with a facing 100 13 of leather or other suitable material, which is cut in a pattern following the shape of the insole, but larger forward of the heel so that it may be turned over the edge and on to the flange 2 from end to end of said 105 flange, said turned portion forming a hold or reinforcement for the sewing heretofore indicated by the numerals 8 and 8^a and which is to all intents and purposes the same in the felt as in the leather as also the tie 110 straps.

In the felt form of insole the asbestos is

on top of the felt and under the facing 13 and all are treated with an antiseptic, also the lining, tie straps and any other fillers which may be used.

- 5 In this arrangement of parts, the outsole may be attached to the welt by stitching much closer in and therefore less exposed, consequently the shoe has a much neater appearance and the stitching is less exposed 10 and altogether it is a better job in every way, because the parts are brought into closer association without in any way complicating the manufacture, in fact the production is much facilitated, especially by the insole 15 flange, which provides a splendid hold for the stitching, as well as for the tie straps or bandages which do so much toward keeping the shoe in shape and incidentally toward supporting the foot and ankle of the wearer, 20 because the tighter the lining and upper are held, the snugger the foot fits to the insole and by the natural pressure on the latter, the closer the said lining and upper gather to and infold the foot and ankle.
- 25 It will thus be seen that a shoe is provided, which will in the ordinary course of events outlast the wear of the outsole and remain in a good condition notwithstanding hard usage and during all the period of 30 wearing be a good and comfortable shoe, retaining its neat appearance and not suffering from tears and rips, so common in shoes, when spreading as a result of the pressure of the foot.
- 35 This invention has many features not at once discernible at a first reading with reference to the drawing, for it is the actual producer who can appreciate the various salient points of the shoe, as for instance 40 the stitching peculiarities and the arrangement and formation of the flange in relation thereto.
- Further it may be pointed out that the gathering up of the strap or bandage ends 45 is much like taking an extra grip of anything in the closed hand, so that there is no possibility of slipping, besides as before mentioned drawing the lining into snug relationship with the foot.
- 50 The manufacturing features are the convenience in providing a good hold for the stitching of the parts together and the simplicity of attaching the sole to the parts thus assembled and yet perform a stitching 55 that is not glaringly exposed.
- Much may be written about cushion soles as considerable has been done toward providing that comfort, but in producing such an article it is not only resiliency that is required for the very material used is that 60 which will more readily absorb perspiration and very soon foul the shoe, so that it is an evil smelling article of wear and with cleanly people not fit for use.
- 65 It is therefore essential to overcome this

difficulty and to do this I make the insole proper of felt and cover this first with a layer of asbestos material and then with a light leather, which makes a facing for the top and a binding for the edge, besides in 70 being drawn together on the underside by reinforcing members, which are stitched as explained to said facing it forms a kind of sling seat for the foot, said stitching including the upper and the lining and in welted 75 shoes the welt. All of said parts adjacent to the foot, such as the insole proper, the facing, the lining, the straps or bandages and the asbestos are treated with an antiseptic preferably a eucalyptus compound 80 and it is much due to the assemblage and construction that this can be done.

Various changes may be made in the manner of making and generally in the construction of the parts of this shoe without 85 departing from the spirit of the invention, so long as it remains within the scope of the claims for novelty following.

What I claim is:—

1. In a shoe, an insole, an upper, a lining, 90 and a tie strap having its ends folded to embrace the edges of the lining and securely attached to said insole, upper and lining.
2. In a shoe, an insole having a flange projecting from its under side adjacent its 95 edge, a welt, an upper, an upper lining, tie straps extending across the under face of said insole having their ends folded to embrace the edges of the lining, means securing said upper and said lining to said 100 flange, and additional means securing said welt, upper and lining to said flange.
3. In a shoe, an outsole, an insole of compressible material having a flange turned out from the surface of the underside adjacent to the edge, a facing on said insole over the upper side and bound around the edge on to said flange, tie straps extending across the under face of said insole, and an upper secured by stitching to said facing, 105 said flange and said tie straps.
4. In a shoe, an outsole, an insole of compressible material having a flange turned out from the surface of the underside near to the edge, an upper, a lining in said upper, a covering for the upper side of said insole, said covering projecting beyond the edge of the insole and turned over on to the underside against said flange, and tie straps extending across said insole and 115 firmly secured to said facing, said upper and said lining and having their ends folded to embrace the edges of said lining.
5. In a shoe, an outsole, an insole having a flange projecting from the underside and 120 extending therearound adjacent its edge and formed from the material of the insole by turning the same out from the surface, tie straps extending across said underside and having folds at the ends, an upper, an up- 130

per lining embraced at its edges in said folds, stitching securing said flange, said straps, said lining and said upper together, a welt, stitching securing said flange, said straps, said lining, said upper and said welt together, and stitching securing said outsole to said welt.

Signed at Montreal, Canada, this 6th day of June, 1917.

JOHN THOMAS TEBBUTT.
